LLP

(57) **CLAIM**

The ornamental design of a television control and pillow
speaker module, as shown.

DESCRIPTION

FIG. 1 is a perspective view, taken from the bottom and
front, of a television control and pillow speaker module, in
accordance with our new design;

FIG. 2 is a reduced perspective view of the television control
and pillow speaker module of FIG. 1, taken from the top and
front; and,

FIG. 3 is a perspective view of the television control and
pillow speaker module of FIG. 1, taken from the bottom and
rear.

The broken line showing of cord in FIGS. 1-3 is for
illustrative purposes only and forms no part of the claimed
design.
